PUZZLE GAME

Rudi W. Mandl, New York, N. Y.

Application February 9, 1943, Serial No. 475,247

10 Claims. (Cl. 273—155)

My invention relates to puzzle games adapted for pastime or amusement and designed to tempt the skill of the participant.

One of the objects of my invention is to provide a puzzle game of the class described which shall be characterized by the novelty and simplicity of its construction and arrangement and which shall at the same time be a challenge to the skill of the user.

Another object of my invention is to provide a puzzle game of the character described which shall be relatively inexpensive to manufacture and which shall be relatively easy and interesting to manipulate and which shall represent generally a novel and useful improvement in the art.

Further objects of my invention will in part be obvious and in part hereinafter pointed out in the description read in conjunction with the accompanying drawing in which,

Fig. 1 is a plan view of a puzzle game constructed and arranged in accordance with my invention and having portions thereof broken away to disclose the interior construction thereof;

Fig. 2 is a plan view of one of the parts of the puzzle game shown in Fig. 1, disassociated therefrom;

Fig. 3 is a plan view similar to Fig. 1, but illustrating a modified form of my invention;

Fig. 4 is a cross-sectional view taken substantially on the line 4—4 of Fig. 1; and

Fig. 5 is a cross-sectional view taken substantially on the line 5—5 of Fig. 2.

Referring now in detail to Figs. 1, 2 and 4 of the drawing, I have shown a puzzle game constructed and arranged in accordance with my invention and comprising a sheet 10 of any suitable relatively rigid material on the nature of heavy paper, Celluloid, cardboard, plastic material or the like, on one surface of which is printed, or otherwise impressed, a series of alternately shaded and light squares 11 which may be arranged in checkerboard fashion. While in accordance with my invention any number of squares 11 may be employed, I have illustrated, for convenience, an arrangement of eight horizontal and eight vertical squares.

Overlying the checkered surface of the sheet 10 are a plurality of strip members 15 to 22. The said strips 15 to 22 are of a width substantially equal to the dimension of the squares 11 and are disposed with their longitudinal edges relatively closely adjacent.

In accordance with my invention, I prefer to mount the strips 15 to 22 on the sheet 10 so that they may be manually slidably moved only in a vertical direction or in other words, so that each of the strips 15 to 22 will at all times overlie and be in alignment with a corresponding vertical row of squares 11.

Any suitable means known to the art may be employed for maintaining the strips 15 to 22 in the above described position, such as, for example, the series of loops 14 at the top of the sheet 10 and the series of loops 16 at the bottom of the sheet 10. Each loop of the loops 14 and 16 may be formed by providing a pair of spaced parallel slits in the sheet 10 of sufficient size to permit the passage therethrough of a strip. The loops 14 as well as the loops 16 may be arranged in staggered relationship to prevent weakening of the sheet 10.

It is thus seen from the above described construction that when it is desired to slidably move a selected strip downwardly, it is merely necessary to grasp the lower end of the said strip and exert a slight pulling force. If it is desired to move the strip upwardly then the upper end of the strip must be grasped.

20 The strips 15 to 22 are preferably of transparent material so that the squares 11 may be seen therethrough at all times. On the upper surface of each of the strips 15 to 22, disposed substantially midway between the ends thereof is a permanently impressed spot which may be of any suitable shape or color, such as for example the black circle 25.

25 The puzzle game is designed to be played or solved by selectively slidably moving the strips 15 to 22, so that the circles 25 are positioned in a predetermined arrangement with respect to the squares 11. A preferred problem is to arrange the black circles 25 so that there will be only one circle 25 in any horizontal, vertical or diagonal row of squares.

30 It is noted that the degree of difficulty of solution of my puzzle game may be increased or decreased by altering the number of squares 11.

35 In Fig. 3 and Fig. 5 I have illustrated a modified form of my invention in which an attempt is made to increase the difficulty of solution of the puzzle game. In this form, I provide a relatively rigid sheet 30 similar to the sheet 10, but which in this case is of transparent material. I provide two independent checkered areas 31 and 32, spaced from each other and each comprising equal squares 35, similar to the squares 11. It is noted that in accordance with my invention the vertical rows of squares 35 in each of the checkered areas 31 and 32 are in alignment. For each vertical row of squares of both areas 31 and 32, I provide a strip 36 similar in construction and purpose to that of the strips 15 to 22. However, each of the strips 36 is provided with a pair of spots 40 and 41, the spot 40 being adapted to occupy a square in the checkered area 31, and the spot 41 occupying a square in the checkered area 32. In order to add to the difficulty of solving the puzzle, as described in connection with the Figs. 1, 3 and 4 form of my invention, I pre-

fer to vary distance between the spots 40 and 41 on one or more of the strips 36, such as for example the strips 36' and 36'' as shown in Fig. 3 of the drawing. It is noted that in strip 36' the spot 40 is disposed one horizontal row of squares higher than the spots 40 on the other strips 36, while it is the spot 41 on the strip 36'' which is disposed one horizontal row of squares higher than the spots 41 on the other strips 36.

It is understood of course that other strips 36 may also have the distance between the spots 40 and 41 at variance with that of the remaining strips 36 and that in such manner the solution to the puzzle game may be made increasingly difficult.

To permit free axial manual movement of the strips 36, 36' and 36'' and at the same time to prevent their lateral displacement, I may provide loops, similar to the loops 14 and 16, or I may employ staggered rows of bands 38 and 39 encircling the strips and having the ends thereof passing through the sheet 30 and knotted.

While it is noted from the drawing that in the Figs. 1, 2 and 4 form of my invention I have illustrated the sheet 10 as being opaque and the strips 15 to 22 transparent and with the said strips overlying the sheet 10, it is understood that the strips 15 to 22 may be made opaque and the sheet 10 transparent and overlying the said strips 15 to 22, as in the Figs. 3 and 5 form of my invention. It is also noted that in the Figs. 3 and 5 forms of my invention the strips 36 and the sheet 30 may be arranged similar to the Figs. 1, 2 and 4 and my invention extends to such construction.

In accordance with the provisions of the patent statutes, I have herein described the principle and operation of my invention, together with apparatus which I now consider to represent the best embodiments thereof, but I desire to have it understood that the structures shown are only illustrative and that the invention can be carried out by other means. Also, while it is designed to use the various features and elements in the combination and relations described, some of those may be altered and others omitted without interfering with the more general results outlined, and the invention extends to such use.

Having described my invention, I claim as new and desire to secure by Letters Patent:

1. In a puzzle game of the class described, the combination of a main body member, a checkered area on said body member comprising horizontal and vertical rows of squares, a longitudinal strip for each vertical row of squares, each strip having a spot or mark thereon disposed between the ends thereof, and means for mounting said strips on said body member for axial movement so that the said spots may be selectively positioned in said squares in an arrangement which constitutes a solution to the puzzle.

2. In a puzzle game of the class described, the combination of a main body member, a checkered area on said body member comprising horizontal and vertical rows of squares, a longitudinal strip for each vertical row of squares, each strip having a spot or mark thereon disposed between the ends thereof, and means for mounting said strips on said body member for axial movement so that the said spots may be selectively positioned in said squares in an arrangement which constitutes a solution to the puzzle, said strips being longer than the vertical dimension of said checkered area so that oppo-

site ends thereof may be selectively grasped for manual manipulation.

3. In a puzzle game of the class described, the combination of a main body member, a checkered area on said body member comprising horizontal and vertical rows of squares, a longitudinal strip for each vertical row of squares, each strip having a spot or mark thereon disposed between the ends thereof, and means for mounting said strip on said body member for axial movement so that the said spots may be selectively positioned in said squares in an arrangement which constitutes a solution to the puzzle, said last named means additionally serving to prevent lateral displacement of said strips.

4. In a puzzle game of the class described, the combination according to claim 1 in which the said strips are disposed in overlying relationship with respect to said checkered area and in which the said overlying strips are of transparent material so that the squares will be visible therethrough at all times.

5. In a puzzle game of the class described, the combination according to claim 1 in which the said main body member is made of transparent material and in which the said strips underlie the said body member so that the said spots thereon are visible through the said body member at all times.

6. In a puzzle game of the class described, the combination of a main body member, a first checkered area on said body member comprising vertical and horizontal rows of squares, a second checkered area on said body member comprising vertical and horizontal rows of squares, the vertical rows of squares of the first checkered area being in alignment with the vertical rows of squares of said second checkered area, a longitudinal strip for each aligned row of squares, each strip having a first spot or mark thereon and a second spot thereon spaced from the first spot, said spots being a predetermined fixed distance apart and means for mounting said strips on said body member for axial movement so that the said first spots may be selectively positioned in the squares of said first checkered area and the second spots in the squares of said second checkered area in an arrangement which constitutes a solution to the puzzle.

7. In a puzzle game of the class described, the combination according to claim 6 in which the said fixed distance between the spots on at least one strip is different from that of the distance between the spots on the remaining strips to render the puzzle more difficult of solution.

8. In a puzzle game of the class described, the combination according to claim 6 in which the said strips are disposed in overlying relationship with respect to said checkered areas and in which the said overlying strips are of transparent material so that the said squares will be visible therethrough at all times.

9. In a puzzle game of the class described, the combination according to claim 6 in which the said main body member is made of transparent material and in which the said strips underlie the said body member so that the spots thereon are visible through the said body member at all times.

10. In a puzzle game of the class described, the combination according to claim 2, in which the said mounting means for the strips comprise a pair of loop members on said body member for each strip and disposed on opposite sides of said checkered area.
